DESIGN FOR A PUSH-BUTTON SIGNALING DEVICE

Michael Hallward, Swampscott, Mass., assignor to
First Industrial Corporation, Wilmington, Del.,
a corporation of Delaware

Application April 17, 1945, Serial No. 119,069

Term of patent 14 years

(Cl. D26—13)

To all whom it may concern:

Be it known that I, Michael Hallward, a subject of the King of Great Britain, residing at Swampscott, in the county of Essex and Commonwealth of Massachusetts, have invented a new, original, and ornamental Design for a Push-button Signaling Device, of which the following is a specification, reference being had to the accompanying drawing, forming a part thereof.

In the drawing,

Figs. 1 and 2 are top and side views of the push-button signaling device showing my new design, and Fig. 3 is an end view thereof.

I claim:

The ornamental design for a push-button signaling device, substantially as shown.

MICHAEL HALLWARD.
